INVENTOR.
Gertrude E. Mallette
BY
Vernon E. Mallette
her ATTORNEY.

UNITED STATES PATENT OFFICE.

GERTRUDE ETHEL MALLETT, OF JUNEAU, TERRITORY OF ALASKA.

ATTACHMENT FOR TYPE-WRITERS.

1,235,354.

Specification of Letters Patent. Patented July 31, 1917.

Application filed October 19, 1916. Serial No. 126,587.

To all whom it may concern:

Be it known that I, GERTRUDE E. MALLETT, a citizen of the United States, residing at Juneau, in the first division of the 5 Territory of Alaska, have invented certain new and useful Improvements in Attachments for Type-Writers, of which the following is a specification.

My invention relates to an improvement 10 in attachments for typewriters, and is used in writing cards such as are employed in card-index and filing systems, and for any other purpose.

The object of my invention is to provide 15 an attachment by which the card will be automatically fed into and discharged from the typewriter, eliminating any necessity for the operator of the typewriter to handle the card.

20 I attain this object by the mechanism which is illustrated in the accompanying drawing in which—

Figure 1 is a cross section of the device taken along the line 1, 1 of Fig. 2;

25 Fig. 2 is a front elevation of the card conveyer;

Fig. 3 is a cross section of the card conveyer taken along the line 3, 3, of Fig. 2; and

30 Fig. 4 is a top plan view of the card feeder box.

The cards A, having been previously packed with a narrow paper tape B folded back and forth under and over each card as 35 shown in Fig. 1, are placed in feeder box C. The end of the tape B, which has been folded with sufficient length at the bottom of the card pack, is drawn through the opening D of box C, Fig. 1, passed under the platen E of the typewriter, as the platen is turned, 40 and over the scale F.

As typewriter platen E is rev'ed, as on 45 any typewriter, tape B, being folded about card A, draws the same from feeder box C through the opening D and into the typewriter, where it is rolled under the platen E into a writing position, above the scale F. As writing proceeds, the card, advanced by 50 the operation of the typewriter spacer, enters the guides G of the discharge conveyer and being held in contact with the platen by the pressure rollers H, is raised until it passes between the rollers J and K of the discharge conveyer, which lift the 55 card from the typewriter. The card continues to rise as the platen is turned, until

it is taken by the rollers L and M, carried up and discharged into the top of feeder box C.

The process is continuous, one card after 60 another being drawn up by the tape from the feeder box into the typewriter, turned through the typewriter as the writing proceeds, and discharged from the typewriter by the card conveyer to the feeder box.

65 The roller N is supported on a spindle P which bears at the ends in extensions Q of the card conveyer guides G. Rollers J and L are supported in a like manner, on similar spindles bearing at the ends in similar extensions of the card conveyer guides. Rollers N, J and L are provided with annular grooves for flexible bands or belts, so that roller N, held in contact with the typewriter platen E, by the weight of the card conveyer, 70 is rotated as the platen is turned, and drives the roller J by means of the band R running in the roller grooves. Roller J in turn drives roller L by means of band S.

75 The feeder box C is attached to any typewriter by means of the metal slips T and U. The spring-clip V directs the card to the typewriter as it leaves the feeder box. The lower edges of the card conveyer guides G are curved to direct the card into the guides 80 of the conveyer as the card moves from the typewriter. The upper ends of the conveyer guides are curved to direct the card from the conveyer to the feeder box.

85 The legs W of the card conveyer are cut and shaped as shown to rest on and grip the lower scale X of the typewriter and are offset as shown in Fig. 2 to accommodate the typewriter mechanism so that the card may be written close to its ends.

95 I claim:

1. In a typewriter the combination with a platen, a container, cards in said container, and a tape folded between said cards and adapted to be received under said platen, 100 whereby the rotation of the platen will draw the cards into writing position on said platen.

2. In a typewriter the combination with a platen, of a container supported above said platen, cards in said container, and a tape folded between said cards and positioned under said platen so that upon the rotation of the platen, the cards will be drawn into writing position thereon.

110 3. In a typewriter the combination with a platen, a container, cards in said container,

feeding means engaging said cards and adapted to be received under said platen, whereby the rotation of the platen will draw the cards into writing position on said platen, guiding means independent of said feeding means, rotary means positioned on said guiding means, and means for actuating said rotary means so that upon the completion of the writing on a card, it will pass through said guiding means by engagement with said rotary means.

4. In a typewriter the combination with a platen, of cards, feeding means therefor, guiding means, rollers on said guiding means, a friction roll in engagement with said platen, and driving means between said rollers and said friction roller, whereby upon the rotation of said platen, the feeding means will feed said cards into the typewriter and upon the continuation of the rotation the cards will be brought into engagement with said rollers for the purpose of discharging said cards from said guiding means.

5. In a typewriter, the combination with a platen, and means for feeding the cards to said platen, of card delivering means mounted in close proximity to said platen, said delivering means consisting of a guide frame spread apart at the platen so as to permit of writing on a card and provided with co-acting delivering rollers, and means on said guide engaging the platen and co-acting delivering rollers for automatically feeding the card therethrough.

6. An apparatus for feeding cards to a typewriter comprising a receptacle for the

cards adapted to be attached to the typewriter, a tape folded between the cards and positioned under the platen for feeding the cards thereto, and means for delivering the cards from the platen back into the receptacle.

7. In a typewriter the combination with a platen, of cards, means for feeding the cards to the platen, and means for delivering the cards from the platen comprising a guide frame, adjustably attached to the typewriter, pressure rollers carried thereby and in engagement with the platen, additional co-acting feed rollers carried by said guide frame, and a friction roller in engagement with said platen, and driving means between said co-acting roller and said friction roller, whereby upon the rotation of the platen the cards will be carried from said platen.

8. In an apparatus for feeding cards to a typewriter comprising a receptacle for the cards adapted to be attached to the typewriter, a tape folded between the cards and positioned under said platen for feeding the cards thereto, and means for delivering the cards from the platen comprising a guide frame attached to the typewriter, feeding rollers carried by said guide frame, additional co-acting rollers carried by said guide frame and a friction roller in engagement with said platen, and driving means between said co-acting roller and said friction roller, whereby upon the rotation of the platen the cards will be carried from said platen.

In testimony whereof I affix my signature.

CERTRUDE ETHEL MALLETT.
